(57) **CLAIM**

The ornamental design for a vehicle windshield, as shown and described.

DESCRIPTION

FIG. 1 is a perspective view of a vehicle windshield; FIG. 2 is another perspective view of the vehicle windshield; FIG. 3 is a front elevational view of the vehicle windshield (as viewed from the front of a vehicle to which it is attached); FIG. 4 is a left side elevational view of the vehicle windshield; FIG. 5 is a right side elevational view of the vehicle windshield; FIG. 6 is a top plan view of the vehicle windshield; FIG. 7 is a bottom plan view of the vehicle windshield; and, FIG. 8 is a rear elevational view of the vehicle windshield. Shading along the periphery of the vehicle windshield illustrates a ceramic paint applied to the windshield.
